UNITED STATES PATENT OFFICE.

JESSE A. CRANDALL, OF BROOKLYN, NEW YORK, ASSIGNOR TO E. I. HORSMAN, OF SAME PLACE.

TOY.

SPECIFICATION forming part of Letters Patent No. 296,536, dated April 8, 1884.

Application filed March 3, 1884. (No model.)

To all whom it may concern:

Be it known that I, JESSE A. CRANDALL, of Brooklyn, in the county of Kings and State of New York, have invented certain new and useful Improvements in Toys; and I do hereby declare that the following is a full, clear, and exact description thereof, reference being had to the accompanying drawings, and to the letters of reference marked thereon, which form 10 part of this specification, in which—

Figure 1 is a front view of my improved toy. Fig. 2 is a back view, showing the clacker and its gravitating arm. Fig. 3 is an edge view. Fig. 4 is a section looking forward, the 15 disk being removed.

This invention is a toy; and it consists in the combination of a rotary disk with a clacker, with or without a figure on the outside of the disk, as will be fully understood from the following description, when taken in connection 20 with the annexed drawings.

A designates a disk, which is applied on a spindle, A², having a handle, A', so that it rotates freely. On the back of this disk is secured a batten, to which is applied a pulley, a, which has a belt reversed and passed around another pulley, a'. This pulley a' is keyed 25 rigidly on the spindle A², and it is flanged to prevent the belt from running off. On this 30 spindle I also key a ratchet-wheel, C, which is between the bifurcated ends of a loaded arm, B, to which is applied a wooden or metal spring, B'. This loaded bifurcated arm and the spring, together with the ratchet-wheel, 35 constitute the clacker, or what has been termed a "watchman's rattle." The shaft g of the lower pinion-wheel extends through the disk A, and has keyed to it a short crank-arm, g', to which is pivoted one end of a connecting-rod, G, the opposite end of which rod is 40 pivoted to a device representing a fence, H. This fence is slotted at h h', and receives through the slots headed pins h' h'', which are fixed into bosses projecting from the face of the disk A. 45 It will be observed that I have a disk applied to a clacker, on the face of which may be painted any design; also, that I have a fence which is actuated to move endwise by rotating the loaded arm.

I contemplate applying any figure to the 50 face of the disk. For instance, I show in my drawings the figure of a man in a cart driving an animal. The man has in one hand the rein, and in the other hand a whip. Now, I desire to have the arms and legs of the man vibrate, 55 and also the head, tail, and legs of the beast also move, representing a man driving a team on the face of the disk.

The wagon I and a thill, together with the body I' of the man and the body I² of the beast, 60 are made of one piece of wood or other suitable material. The arms J of the man articulate about the pivot j, and the lower legs articulate about the pivot j'. Both legs of the man are made of one piece. The legs, arms, 65 and the head of the man, and also the head of the horse and its legs and tail, vibrate synchronously. This is effected by the following connecting-rods, all of which are clearly shown in Fig. 4: The rod R connects the head to the 70 body, the rod R' connects the body with the posterior part of arm of the man, the rod R² connects the said arm with the legs, the rods S S' connect the legs with the fence, and the rod S² connects the fence with the pivoted 75 head of the beast.

It will thus be seen that by simply rotating the clacker the several parts of the figure are put in motion, representing a man driving a horse on a race-track.

It is obvious that any other automaton may be substituted for the figure herein described.

The disk A may be actuated by a spiral spring applied on the spindle of the handle A', which spring would be inclosed in a case and 85 provided with a key-post to be wound up at pleasure.

It is obvious that when a spring is employed the clacker may be dispensed with, or both may be used on the same toy.

Having thus fully described my invention, what I claim as new, and desire to secure by Letters Patent, is—

1. The combination of a clacker having a disk applied on the spindle and an automaton 95 on the face of the disk, substantially as described.
2. The combination of a loaded clacker ap-

plied on a spindle having a handle secured to it, a disk, and an automaton applied on the face of the disk, substantially as described.

3. The combination of a loaded clacker, pulleys $a' a'$, a disk applied on the spindle of the clacker, and an automaton on the face of the disk, substantially as described.

In testimony that I claim the foregoing as my own I affix my signature in presence of two witnesses.

JESSE A. CRANDALL.
